ELECTRICAL DISCONNECT

Quentin Berg, 1550 Brandt Ave., New Cumberland, Pa.
Filed Mar. 14, 1957, Ser. No. 646,139
9 Claims. (Cl. 339—256)

This invention relates to electrical disconnects and has particular reference to a novel and improved construction of the socket element.

This application is a continuation-in-part of my prior application Serial No. 546,091, filed November 10, 1955, and now abandoned, for "Electrical Disconnect."

Electrical disconnects of the type to which the invention relates comprise a slot type socket for telescopically receiving and yieldably holding a blade type connector. Socket elements of disconnects now in use are not entirely satisfactory for various reasons. In some cases the design is such that the insertion of the blade type connector element is difficult. In other cases the gripping or locking action between the two elements when assembled is poor, thus producing undesirable electrical performance characteristics. Lack of uniformity of quality has also been frequently encountered in connection with disconnects of this type now in use.

The present invention is directed to a simple construction for socket elements of disconnects which eliminate such objections and difficulties frequently encountered in disconnects now in use and which construction lends itself to uniformity in construction and economy in the cost of production.

A principal object of the invention therefore is to provide a new and improved construction for socket elements of disconnects.

Other and further objects of the invention will be apparent from the following description and claims and may be understood by reference to the accompanying drawings, which by way of illustration show preferred embodiments of the invention and what I now consider to be the best mode in which I have contemplated applying the principles of my invention. Other embodiments of the invention may be used without departing from the scope of the present invention as set forth in the appended claims.

In the drawings:

FIGURE 1 is a plan view of a strip of disconnect elements illustrating the construction thereof and some of the steps in the manufacture thereof;

FIGURE 2 is an end elevational view of a disconnect socket element;

FIGURE 3 is a sectional view taken along the line 3—3 of FIGURE 1;

FIGURE 4 is an enlarged sectional view taken along the staggered line 4—4 of FIGURE 1;

FIGURE 5 is a plan view of a disconnect showing the complete assembly thereof;

FIGURE 6 is a sectional view taken along the line 6—6 of FIGURE 5; and

FIGURE 7 is a perspective view of a modified form of the invention.

As shown in FIGURE 5, the disconnect comprises a blade type connector 10 and a slot type socket 12, the latter being adapted for telescopically receiving and yieldably holding the connector 10. The socket element 12 includes integral provisions in the form of prongs 14 for clamping a wire type of current conductor 16 to the disconnect element 12 and provisions in the form of prongs 18 for clamping around the insulation 20 of the conductor 16.

Preferably the socket elements 12 are made from an integral strip of thin sheet metal such as brass which is subjected to a series of die operations so as to form a strip of elements 12 connected as illustrated in FIGURE

2

1, which shows a complete or preformed element connected to an incomplete element 12A.

Each socket element comprises a generally flat rectangular sheet metal portion 22 which is diagonally twisted or racked so as to form a diagonal bend or crest 24 between the corners thereof. I have found that good results are obtained where a twist of about 4° is given the portion 22. Integral laterally projecting flanges or ears 25 are bent generally normal to the portion 22 and are then bent back toward each other in spaced relation with the portion 22 so that the overhanging ends 26 are spaced from the portion 22 and form the opposite side of the socket indicated generally at 28. Thus the socket 28 is defined by a pair of channels 29 which are interconnected by the portion 22.

One end of the socket 28 defines an entrance end 30 thereto through which the blade type connector 10 may be inserted into the socket 28, the side edges of the blade 10 being received in the channels 29. The crest of the bend 24 projects into the socket 28 and forms a spring which cooperates with the opposite side of the socket provided by the ends 26 to grip the connector 10 for yieldably holding such connector in the socket 28. The portion 22 may be peened or thinned to work harden it, thus providing a higher yield point and hence greater deflection or spring action in the bend 24. Preferably the socket is provided with a detent 32 on the crest of the bend 24 for cooperation with a similar detent 34 in the element 10 for locating the elements relative to each other in their assembled position. The ends of the laterally projecting portions 26 which are bent toward each other and downwardly toward base portion 22 are inclined relative to each other, and channels 29 are skewed relative to each other, lengthwise of the socket so as to increase the gripping action between the socket element 12 and the blade type connector 10.

Additionally, if the diagonally opposite corners of the folded-over ends 26 are depressed, considerable additional spring action may be obtained thereby. In the present instance I have shown the corners 36 and 38 as being depressed. This not only stiffens the ends 26 but also exerts a racking or twisting action on the element 10 about the diagonal bend 24. However, this deflection of the ends 36 and 38 of the portions 26 may be omitted in some cases, particularly if the portion 22 is twisted an adequate amount. The twisting and work hardening of the portion 22 stiffen the same and effect the skewing of the channels 29 while permitting yielding thereof when the element 10 is inserted in the socket 28, causing the element 10 to be twisted and gripped thereby in the socket 28. This construction makes it possible to space the sides of the socket 28 so as to permit easy initial insertion of the element 10 in the socket 28. The detents 32 and 34 locate and lock the elements 10 and 12 in their assembled position and also serve to increase the gripping action therebetween. However, the detents 32 and 34 may be omitted if the bend 24 is sufficient to produce the same gripping action. However, the detents 32 and 34 produce a snap action which is not obtainable if the detents 32 and 34 are omitted. The type of locking action obtained between the elements 10 and 12 can be varied by controlling the clearance between the portions 22 and 26 in addition to the amount of the diagonal bend 24. More diagonal bend gives greater snap action, while less clearance between the portions 22 and 26 gives greater drag throughout insertion and extraction.

To facilitate insertion of the blade 10 in the socket 12, the latter may be provided with a guide flange 39 which projects downwardly below the plane of the portion 22 at the entrance end 30 of the socket, and which flange

39 cooperates with the blade 10 for guiding the same into the socket 28.

The metal stock which forms prongs 14 which clamp around the wire 16, as well as the connecting portion 40 therebetween, are corrugated as at 42 to improve the grip of the prongs 14 on the wires 16 and, as illustrated in FIGURES 1 and 3, the corrugations in the prongs 14 are offset from those in the portion 40 so that when the prongs 14 are crimped around the wire 16 as shown in FIGURES 5 and 6 the crests of the corrugations bearing against one side of the wire 16 are offset from those on the opposite side, thereby eliminating pinching of the wire which would otherwise occur and, in addition, providing a better grip between the corrugations 42 and the wire 16 as this arrangement will produce a pronounced corrugation in the wire 16. The prongs 18 are wrapped and clamped around the insulation 20 thereby to secure the socket element 12 to the insulation 20.

The prongs 14 when clamped around the wire 16, as shown in FIGURES 5 and 6, cooperate with the portion 40 with which the prongs are integral to form a corrugated barrel or ferrule 43 inside of which the wire 16 is firmly anchored and tightly gripped. The corrugation of such barrel stiffens the same and the end of the disconnect, and also compensates for variations in size of the wire 16, and insures a uniformly good connection between such wire and the disconnect. The corrugation of the barrel also in some cases permits the use of thinner stock. To further stiffen the disconnect element I provide a longitudinally extending corrugation or rib 41 in the metal stock 22 which extends between the socket proper and the ferrule 43.

In the arrangement illustrated in FIGURE 7 the construction is essentially the same as that previously described except that the wall portion 50 of the socket which interconnects the channels 29 is offset from the channels 29 so that the socket is defined essentially by the channels 29. However, since the metal stock which forms the wall 50 is racked or twisted to form a crest 52 like the crest 24, it will be apparent that the channels 29 are not aligned, but actually are skewed with respect to each other, as is the case of the channels 29 in the previous modification. The skewed relation of the channels 29 has been found to be adequate usually to firmly retain the blade type connector 10 in the socket. The connecting portion 50 of the socket may be embossed to define a detent 54 similar to the detent 32 and for cooperation with the detent 34 in the spade 10 for locating the spade 10 in the socket of the disconnect of FIGURE 7. The disconnect of FIGURE 7, like that of FIGURE 1, is made from an integral strip of thin sheet metal, such as brass, which is subjected to a series of die operations so as to form a strip of disconnect elements, one of which is shown in FIGURE 7. The offset relation of the wall 50 with the channels 29 has been found to add additional stiffness to the disconnect.

Because of the efficient use of the metal in the construction herein disclosed, it is possible to use substantially less metal than otherwise required without a sacrifice in the required strength or electrical efficiency of the element.

While I have illustrated and described preferred embodiments of my invention, it is understood that these are capable of modification, and I therefore do not wish to be limited to the precise details set forth but desire to avail myself of such changes and alterations as fall within the purview of the following claims.

I claim:

1. An electrical connector element comprising an integral piece of thin sheet metal formed to provide a slot type socket for telescopically receiving and yieldably holding a blade type connector, said element comprising a flat sheet metal portion which is provided with a bend thereacross, said portion forming one side of said socket

with said bend thereacross and having integral laterally projecting portions the ends of which are flat and bent toward each other in spaced generally parallel relation with a respective adjacent portion of said one side so as to form opposed channels which are disposed in skewed relation with one another and the opposite side of said socket, said socket at one end thereof being formed to define an open entrance through which the blade type connector may be inserted into said socket, the crest of said bend projecting into said socket and cooperating with the skewed channels to grip an inserted blade type connector for yieldably holding the blade type connector in said socket, said socket being provided with a detent on the crest of said bend, the flat ends of said laterally projecting portions which are bent toward each other being free and inclined relative to said one side and to each other lengthwise of said socket, and said connector having other integral provisions for connecting a current conductor thereto.

2. An electrical connector element comprising an integral piece of thin sheet metal formed to provide a slot type socket for telescopically receiving and yieldably holding a blade type connector, said element comprising a flat rectangular sheet metal portion which is twisted to form a diagonal bend thereacross, said portion forming one side of said socket with said bend thereacross and having integral laterally projecting portions the end of each of which is flat and bent in spaced generally parallel relation with a respective adjacent portion of said rectangular portion so as to form the opposite side of said socket, said sides of said socket at one end thereof being formed to define an open entrance through which the blade type connector may be inserted into said socket, said diagonal bend projecting into said socket and cooperating with the opposite side thereof to grip an inserted blade type connector for yieldably holding the blade type connector in said socket.

3. A connector element according to claim 2 wherein the ends of said laterally projecting portions are free and inclined relative to said one side and to said twisted portion lengthwise of said socket.

4. An electrical connector element comprising an integral piece of thin sheet metal formed to provide a slot type socket for telescopically receiving and yieldably holding a blade-type connector, said element comprising a flat rectangular sheet metal portion which is twisted to form a bend thereacross, said portion forming one side of said socket and having a pair of integral laterally inwardly projecting wing portions defining the opposite side of said socket, the free ends of said wing portions being bent toward each other in spaced relation with said rectangular portion and the said ends of said wing portions being skewed relative to each other, said sides of said socket at one end thereof being formed to define an open entrance through which the blade type connector may be inserted into said socket, the crest of said bend projecting into said socket between the free ends of said wing portions and cooperating therewith to grip an inserted blade-type connector for yieldably holding the blade-type connector in said socket.

5. An electrical connector element comprising an integral piece of sheet metal formed to provide a slot type socket for telescopically receiving and yieldably holding a blade connector, said element comprising a generally rectangular sheet metal portion forming one side of said socket and having integral laterally projecting portions the free ends of which are flat and flexible and project toward each other in spaced relation with a respective adjacent portion of said one side so as to form the opposite side of said socket, said sides of said socket at one end thereof being formed to define an open entrance through which the blade connector may be inserted into said socket, said one side of said socket having a detent and cooperating with the opposite side of the socket to frictionally grip an inserted blade connector for yieldably frictionally holding the blade connector in said socket, said flat ends of

said laterally projecting portions being twisted relative to each other so that the free edges of said ends lengthwise of said socket are skewed relative to each other thereby to exert a twisting force on an inserted blade connector, the width of said socket throughout its length being substantially uniform.

6. An electrical connector element comprising an integral piece of sheet metal formed to provide a slot type socket for telescopically receiving and yieldably holding a blade type connector, said element comprising a rectangular sheet metal portion forming one side of said socket and having integral laterally projecting wing portions the ends of which are bent toward each other in spaced relation with said rectangular portion so as to form the opposite side of said socket and to define a pair of spaced channels along the edges of said sides, said sides of said socket at one end thereof being formed to define an open entrance through which the blade type connector may be inserted into said socket, said rectangular portion having a detent and cooperating with the opposite side of the 20 socket to position an inserted blade type connector in said socket, said channels being disposed in skewed relation with respect to each other for yieldably holding an inserted blade type connector in said socket.

7. An electrical disconnect comprising an integral sheet of metal bent to form a socket and a ferrule, said socket comprising a pair of spaced channels disposed in skewed

5 relation with respect to each other longitudinally of the socket for gripping a blade type connector inserted in said socket, and an integral portion continuously interconnecting said channels and said ferrule, and extending between the channels and longitudinally of the socket at least half the length of said channels.

8. An electrical disconnect as in claim 7 wherein said portion is formed to define an integral rib extending between said socket and ferrule.

10 9. An electrical disconnect as in claim 7 wherein said interconnecting portion is offset from said channels.
